US0D1108295S

(12) **United States Design Patent** (10) **Patent No.:** **US D1,108,295 S**
(45) **Date of Patent:** **** Jan. 6, 2026**

(54) **WATCH STRAP CONNECTOR**

(71) Applicant: **Shenzhen Xinbin Electronic Technology Co., Ltd.**, Shenzhen (CN)

(72) Inventor: **Zejia Ou**, Guangdong (CN)

(73) Assignee: **Shenzhen Xinbin Electronic Technology Co., Ltd.**, Shenzhen (CN)

(**) Term: **15 Years**

(21) Appl. No.: **29/915,971**

(22) Filed: **Nov. 7, 2023**

(51) **LOC (15) Cl.** **11-01**

(52) **U.S. Cl.**

USPC **D11/94**

(57) **CLAIM**

The ornamental design for a watch strap connector, as shown and described.

DESCRIPTION

FIG. 1 is a perspective view of a watch strap connector showing the new design;

FIG. 2 is another perspective view thereof;

FIG. 3 is a perspective view of the watch strap connector, shown in an alternate configuration;

FIG. 4 is a front elevation view of the watch strap connector;

FIG. 5 is a back elevation view thereof;

FIG. 6 is a left-side view thereof;

FIG. 7 is a right-side view thereof;

FIG. 8 is a top plan view thereof; and,

FIG. 9 is a bottom plan view thereof.

The broken lines depict portions of the watch strap connector that form no part of the claimed design.

1 Claim, 9 Drawing Sheets
